LETTER FOLDING GUIDE

Sidney Glass, 320 N. Palm Drive, Beverly Hills, Calif.

Filed July 11, 1962, Ser. No. 70,885

Term of patent 7 years

(Cl. D74—1)

FIG. 1

FIG. 3

FIG. 2

FIG. 4

FIG. 1 is a front perspective view of a letter folding guide, showing my new design;

FIG. 2 is a rear elevational view thereof;

FIG. 3 is an edge elevational view as seen from the top of FIG. 2; and

FIG. 4 is an edge elevational view as seen from the right of FIG. 2.

I claim:

The ornamental design for a letter folding guide, substantially as shown.
